UNITED STATES PATENT OFFICE

WENDELIN WEIS, OF ST. PAUL, MINNESOTA.

IMPROVEMENT IN EGG-BOXES.

Specification forming part of Letters Patent No. **179,985**, dated July 18, 1876; application filed June 5, 1876.

To all whom it may concern:

Be it known that I, WENDELIN WEIS, of St. Paul, in the county of Ramsey and State of Minnesota, have invented certain new and useful Improvements in Egg-Carriers; and I do hereby declare that the following is a full, clear, and exact description thereof, which will enable others skilled in the art to which it appertains to make and use the same, reference being had to the accompanying drawings, and to letters of reference marked thereon, which form a part of this specification.

In the drawings, Figure 1 represents my tray complete. Fig. 2 is an elevation view of one of the outer strips, while Fig. 3 shows a modification of the same principle. Fig. 4 is a detail view of the two two central partition-strips.

The letters of reference are as follows: A is the outer strip. *a a* are the segmental tongues. *a'* is the straight slot. In the modification view, Fig. 3, B is the strip having one tongue, *b*, and two straight slots, *b' b'*.

My invention has as its object an improvement on the egg-carrier granted to me December 15, 1874, numbered 157,896, in that, first, the interlacing strips are flush strips—that is, of one and the same width—whereby a constant and uniform pressure is borne by both the cross-sections, and hence the tray is less liable to breakage and injurious derangement. Strips of this construction, whereby both their upper and lower edges form, respectively, continuous plane surfaces, I term “flush strips.” Second, each of the outer strips is engaged to the connecting parts partly by the segmental tongues of its body proper locking in straight slots of said connecting-strips, and partly by a tongue of such connecting-strip locking into a straight slot of said outer strip. By such latter means a more secure and durable lock is obtained for the parts, in that as either outer strip is subjected to a force tending to press the same from the tray-frame, such a force is met not only by the tongue resisting according to the strength of its plane dimension and flat width, but such force is further opposed by the right-angular strength of the two pieces rigidly connected at either end, and formed by cutting the straight slot in the strip for the introduction of the tongue of the

interlocking strip. In this mode of locking it is seen that the tray is secured and strengthened in the jointure of its parts by not depending solely upon the resistance of the tongues acting in a line of force opposite to their length, and which must necessarily be small, on account of the tongues being secured only at their base end, while the free end combined with the arc-shaped formation of the tongue renders the latter's entire strength only equal to one-half of what it would be if it were a continuous piece, and connected at either end to the body of the strip, as is the case in the construction of the remaining locking device used in the same strip, and in combination with this immediately above-described lock. The third feature of my invention is, that middle partition-strips are united at the center of the tray by double tongue and slot, one of each being respectively formed in both the joining partitions. Hence, it is observed, all tendency to rack or tear the frame apart is resisted, and the partitions cannot at their center be disengaged or separated in any direction.

The operation of the tray is so well known as not to require explanation, it being evident that after one tray is filled a diaphragm or horizontal piece may be laid over such packed tray, and upon the upper surface of same a second tray may be placed, which, after being filled, may also be supplemented by other trays.

Having fully described my invention, what I claim as new, and desire to secure by Letters Patent, is—

An egg-tray constructed of flush strips locked by segmental tongues, and engaging slots interchangeably formed on each side strip, in combination with partition-strips centrally secured by the tongue and slot of the one partition engaging, respectively, with the slot and tongue of the crossing partitions, substantially as and for the purpose described.

In testimony that I claim the foregoing as my own I affix my signature in presence of two witnesses.

WENDELIN WEIS.
